Primary Examiner—Ralf T. Seifert*Attorney, Agent, or Firm*—Cushman, Darby & Cushman[57] **CLAIM**

The ornamental design for a finger ring, as shown and described.

DESCRIPTION

FIG. 1 is a top plan view of a finger ring showing my new design;

FIG. 2 is a left side elevational view;

FIG. 3 is a right side elevational view;

FIG. 4 is a front elevational view; and,

FIG. 5 is a rear elevational view.

It being understood that the interior of the ring, not shown, is plain and unornamented.

Fig. 1.Fig. 2.Fig. 3.Fig. 4.Fig. 5.
